UNITED STATES PATENT OFFICE

114,398

DESIGN FOR A TEXTILE FABRIC

Louis Kaufman, New York, N. Y.

Application January 11, 1939, Serial No. 82,273

Term of patent 3½ years

To all whom it may concern:

Be it known that Louis Kaufman, a citizen of the United States, residing at 555 Eighth Avenue, city of New York, in the county of New York and State of New York, have invented a new, original, and ornamental Design for a Textile Fabric, of which the following is a specification, reference being had to the accompanying drawing, forming part thereof.

Fig. 1 is a plan view of the textile fabric showing my new design, and

Fig. 2 is the elevational view thereof.

The design is characterized by parallel rows of yarn cords arranged in crisscross relation on a puckered background forming a series of substantially diamond-shaped elements and tufts being applied to the center of each diamond as shown.

I claim:

The ornamental design for a textile fabric, substantially as shown and described.

LOUIS KAUFMAN.
